UNITED STATES PATENT OFFICE.

WILLIAM STEVENS, OF PHILADELPHIA, PENNSYLVANIA.

HATCHWAY FOR ELEVATORS.

SPECIFICATION forming part of Letters Patent No. 287,590, dated October 30, 1883.

Application filed March 23, 1883. (No model.)

To all whom it may concern:

Be it known that I, WILLIAM STEVENS, of the city of Philadelphia, county of Philadelphia, and State of Pennsylvania, have invented an Improvement in Hatchways for Elevators, of which the following is a specification.

My invention has reference to elevators, but more particularly to the hatch-doors thereon; and it consists in hinging the door to the floor at one side, and providing said door with a hinged section adapted to automatically fold up in the act of raising the door, so as to clear the guide-post, and in details of construction, as fully set out in the following specification, and shown in the accompanying drawings, which form part thereof.

Heretofore elevators having the guide-posts arranged vertically through two diagonal corners have had their hatch-doors divided into two parts, and divided on a diagonal line from post to post. This has the objection, however, of obstructing two approaches to the elevator, and in many cases could not be used.

The object of my invention is to so construct the hatch-doors of a diagonal guide-post elevator that three approaches are available.

In the drawings, Figure 1 is a perspective view of my improved elevator hatch-door in the act of being opened. Fig. 2 is a plan view of same with the door closed, and Fig. 3 is a plan view of same with the door opened.

45 A is the hatchway.

B are the diagonally-arranged guide-posts for the elevator cage or platform.

C is the hatch-door, and almost entirely covers the hatchway, and is hinged to the floor at D on one side.

E is a small flap hinged to one side of the door C at F, and when turned up at or near right angles with the door C it clears the guide-post as the said door is raised. To cause said flap to turn up quickly I provide the following mechanism: A shaft, G, is carried in bearings H on door C, and one end thereof is provided with an arm, g, which works under a roller, I, secured to the flap E, and on the other end with an arm, g', arranged almost vertical when the flap is closed. Pivoted to the end of arm g' by a universal joint, J, is a thrust or stay rod, K,

the other end of which is pivoted by a universal joint, L, to the floor, as shown. Now, when the door is closed, the flap is down, and the arm g' is almost vertical to the door; but upon raising, the shaft G is quickly rotated by the arm g' and resistance offered by the stay-bar K, and the flap is raised at right angles to the door C and in time to clear the post B as the door is fully opened; and in closing, the door is almost closed before the flap turns down. This quick movement of the flap is necessary to enable it to readily clear the post in opening and closing.

I do not limit myself to the specific construction of mechanism shown, as it may be modified in various ways without in any wise departing from my invention.

Having now described my invention, what I claim as new, and desire to secure by Letters Patent, is—

1. A hatchway for elevators, provided with a door hinged on one side of said hatchway only, the said door having a hinged flap, and combined with means to automatically raise said flap to a substantially perpendicular position upon the door in the act of raising the same, substantially as and for the purpose specified.

2. A hatchway for elevators, provided with a door hinged on one side thereof, having a hinged flap, combined with means to raise said flap rapidly, and then hold it at or near right angles with reference to said door upon opening the same, and reversely upon closing said door, to cause said flap to avoid collision with the guide-posts, substantially as and for the purpose specified.

3. The combination of hatchway A, guide-posts B, door C, hinged at D, and flap E, hinged to the door at F, substantially as and for the purpose specified.

4. The combination of hatchway A, guide-posts B, door C, hinged at D, and flap E, hinged to the door at F, shaft G, having arms g g', and stay-rod K, substantially as and for the purpose specified.

In testimony of which invention I hereunto set my hand.

WILLIAM STEVENS.
